UNITED STATES PATENT OFFICE.

JOHN KOERBER, OF AKRON, OHIO.

TELLTALE FOR LOCKS.

SPECIFICATION forming part of Letters Patent No. 718,359, dated January 13, 1903.

Application filed May 29, 1902. Serial No. 109,499. (No model.)

To all whom it may concern:

Be it known that I, JOHN KOERBER, a citizen of the United States, residing at Akron, in the county of Summit and State of Ohio, have 5 invented a certain new and useful Improvement in Telltales for Locks, of which the following is a complete specification.

My invention has a general relation to improvements in telltale devices for locks that 10 indicate by some mechanism or indicia what key has been used to operate the lock.

The invention contemplates a device to be associated with the lock of a door the proprietor of which has numerous employees to 15 each of whom he intrusts a particular key that will turn the lock.

The object of my invention is to provide a new and improved apparatus which will be operated by the introduction and use of each 20 key and will by suitable mechanism indicate the particular key used.

To the accomplishment of the aforesaid object my invention consists in the peculiar and novel construction, arrangement, and 25 combination of parts hereinafter described and then specifically pointed out in the claims, reference being had to the accompanying drawings, which form a part of this specification.

30 In the accompanying drawings, in which similar reference-numerals indicate like parts in the different figures, Figure 1 is a front view; Fig. 2, a similar view opened; Fig. 3, the same in section at the line $x-x$ of Fig. 1, 35 connected with a door having a mortise-lock; and Fig. 4, a group of three keys each adapted to operate the lock and to differently actuate the telltale.

Referring to these figures, 1 is a case, preferably circular in form and of metal, with a flat back and projecting rim, to one side of which rim is secured by a hinge 2 a cover 3, which forms a front face for and closes the case and is secured by a lock 4 of any desired or approved kind.

45 Projecting from and secured in the back of the case 1 are a series of small shafts or studs 5, 6, and 7, on which are severally mounted sleeves 8, 9, and 10, on each of which 50 sleeves are respectively projecting lugs 11, 12, and 13, arranged at different distances from said back plate and severally adapted

to be engaged by a lug on the key that is used to operate the lock.

The keys 14, 15, and 16 are each adapted 55 to open the door-lock 20, which lock may be of any approved or desired pattern, and each key-shaft bears a stud (marked respectively, 17, 18, and 19) of like size situated at different distances back from the end of the key 60 and severally arranged to engage one of the lugs 11, 12, and 13, respectively, when the key is used and as the key is turned push it around on its respective shaft 5, 6, or 7. Hence whichever key is used to open the 65 lock it will, by means of the contacting lugs, turn one of the sleeves 11, 12, or 13, thereby leaving the lug of that sleeve on the inside of the case out of position.

When the proprietor desires to know who 70 opened the door, he opens case 1, and a moment's inspection of the lugs 11, 12, or 13 tells him which key was used to unlock the door and enables him to fix the responsibility on the person to whom he intrusted the key. 75

In the drawings no attempt has been made to show any lock mechanism, as that forms no part of my invention, but only so much has been made as illustrates the connection of my device with such mechanism, nor is it 80 intended by the drawings to confine the invention to mortise-locks, as it is manifestly applicable equally to flush locks.

Having thus described my invention, what I claim, and desire to secure by Letters Patent, is—

1. An improved telltale for locks consisting of a series of lugs located around a common center, arranged at different distances from a common face, severally revolvably 90 mounted, and severally arranged to be engaged by a lug on a key-shaft, substantially as shown and described.

2. An improved telltale for locks consisting of an inclosing case having mounted therein a number of revolving sleeves, said sleeves bearing lugs, said lugs situated at different distances from a common face, with keys capable of operating said lock bearing lugs severally adapted to singly engage one of said 100 sleeve-lugs, substantially as shown and described.

3. A telltale for locks consisting of a casing to inclose a keyhole, sleeves bearing lugs

mounted in said casing to designate the particular key used, in combination with a number of keys each bearing lugs differently situated on the shanks thereof and arranged to engage the lugs on said sleeves, substantially as shown and described.

4. A telltale for locks consisting of a casing to inclose the keyhole of a lock, means for permitting the locking thereof, lug-bearing sleeves mounted in said casing adapted to be operated by the revolution of a key in said lock in combination with a number of keys each bearing means on their shanks differently located with reference to the lock-operating portion of said keys, substantially as shown and described.

5. A telltale for locks consisting of a casing to inclose the keyhole of said lock, means to permit the passage of a key through said casing, indicating mechanism mounted in said casing consisting of differently-located lugs to be singly operated by determinate keys, substantially as shown and described.

6. The combination in a telltale for locks of a casing to surround the keyhole of a lock, means to permit the passage of a key through said casing, indicating mechanism to be operated by different keys, in combination with keys bearing projections to actuate said mechanism, substantially as shown and described. 30

7. The combination in a telltale for locks, of a casing to inclose the keyhole of a lock, an opening to permit the passage of keys through said casing into said lock, lug-bearing sleeves situated in said casing, and keys bearing means to individually operate a determinate lug-bearing sleeve to cause it to partially rotate, substantially as shown and described.

In testimony that I claim the above I hereby 40 unto set my hand in the presence of two subscribing witnesses.

JOHN KOERBER.

In presence of—

C. P. HUMPHREY,
C. E. HUMPHREY.
